UNITED STATES PATENT OFFICE.

NATHANIEL O. GOLDSMITH, OF CINCINNATI, OHIO, ASSIGNOR TO THE WEIR FROG COMPANY, OF SAME PLACE.

SWITCH-STAND.

SPECIFICATION forming part of Letters Patent No. 408,174, dated July 30, 1889.

Application filed March 30, 1889. Serial No. 305,414. (No model.)

To all whom it may concern:

Be it known that I, NATHANIEL O. GOLDSMITH, a citizen of the United States, and a resident of Cincinnati, in the county of Hamilton and State of Ohio, have invented certain new and useful Improvements in Automatic Switch-Stands, of which the following is a specification.

My invention relates to an automatic switch-stand.

The object of my invention is to provide a strong, durable, and positively-working automatic switch-stand, all of which will be fully set forth in the description of the accompanying drawings, making a part of this specification, in which—

Figure 1 is a central vertical section of my improved switch-stand. Fig. 2 is a sectional elevation of the top, showing the stand locked. Fig. 3 is an elevation of the switch-stand with the lower portion of the stand broken off to show the position of the parts when in position for being thrown. Fig. 4 is a top plan view of the stand with the target-shaft in section. Fig. 5 is a section on line *x x*, Fig. 1; and Fig. 6 is a section on line *y y*, Fig. 3.

1 represents the crank; 2, the crank-rod, which passes up through the stand, and to 30 which the crank 3 is attached. The crank-rod is shown round at 4 and 5 for journaling in the bottom and top of the stand. The bottom section of the stand 6 is on its top face provided with annular clutch 7. It has 35 four clutch-teeth in the annulus round the central shaft. The lower section is secured to the upper or the barrel portion of the switch-stand by bolts A. This upper portion is hollow, so as to employ a coil-spring 8, the 40 lower end of which seats upon the hub or lug 9 and the upper end against the disk 10, which is secured to the crank-shaft by the pin 11. The central portion of the crank-shaft is made square and slides freely through 45 the upper clutch 7, as will be hereinafter explained.

The clutch 9 on the crank-shaft is provided with teeth engaging with those of clutch 7. In Fig. 3 the crank-rod 2 is shown raised, so 50 that the teeth of clutch 7 are disengaged from the teeth of clutch 9, which allows the crank-shaft to turn for throwing the switch.

14 represents a lug on the forward end of the lever 12. As the lever 12 is raised, the said lug 14 strikes against the immovable table 15 55 on the top of the stand, raising the crank-shaft 2 up centrally, when said lever is brought into the position shown in Fig. 3, and thereby disengaging the clutches, after which the crank-shaft 2 may be turned in 60 either direction by the lever.

In order to prevent the lever 12 from being dropped until the crank-shaft is turned far enough to either fully open or close the switches, I provide a segmental guide 16, 65 which is mounted upon the table 15. As soon as the lever is turned to move the switch, the lug 14 comes opposite said guard, Fig. 3, and the lever cannot be depressed until it is brought round, say, to the position shown in 70 Fig. 4, when the lever may be dropped into position shown in Fig. 2, the switch being either opened or closed. It can be locked in this position by the hasp of a lock passing through the orifice 18. (See Fig. 2.) 75

It will be seen that the lever raises the crank-shaft 2 freely up far enough to disengage the teeth-clutches 7 and 9. This movement has no effect upon the spring, as it is lifted bodily with the shaft, the pin between the clutches lifting the upper clutch and spring. Stops 20 and 21 are provided upon each side of the clutch and base of the stand, Fig. 5, to limit the turning of the crank-shaft. When the lever is down, as shown in 80 Fig. 2, the lug 19 prevents it and the crank-shaft from being raised. Consequently when the pressure is applied by the train-wheels to the crank-shaft to turn it automatically this imparts pressure to the inclined teeth of the 85 clutches 7 and 9, the clutch 9 sliding upon the shaft 2 and compressing the spring 8 sufficient to allow the teeth of clutch 9 to pass the teeth of clutch 7. It will thus be seen that by means of the lever 12 the switch is 90 locked, except against the great strain of the train, and yet when raised in horizontal position the switch can be turned freely without being turned against the strain of the spring. This is accomplished by securing 100 one clutch to the switch-stand and one to the crank-shaft, allowing the latter to slide freely in the stand, except when it is locked against such movement.

Having described my invention, what I claim is—

1. The combination of a sectional switch-stand the lower part of which is provided with a stationary toothed clutch 7, the vertically-movable crank-shaft 2, the toothed clutch 9, adapted to slide vertically upon the crank-shaft, a spring 8, movable bodily with the crank-shaft and compressed by the upward movement of the sliding clutch, and a lever 12, connected with the crank-shaft, substantially as described.

2. The combination of a switch-stand having a stationary toothed clutch, the vertically-movable crank-shaft, the toothed clutch arranged to slide vertically on the crank-shaft, and a spring movable bodily with the crank-shaft and located thereupon above the sliding clutch to press the latter in engagement with the stationary clutch, substantially as described.

3. The combination of a switch-stand hav-

ing a stationary toothed clutch, the vertically-movable crank-shaft, the toothed clutch arranged to slide vertically on the crank-shaft, 25 a spring located on and movable bodily with the crank-shaft and acting to press the sliding clutch in engagement with the stationary clutch, and a vertically-swinging lever which in its vertical movement acts on the switch-stand to raise the crank-shaft and spring, substantially as described.

4. In combination with the switch-stand, the clutch 7, attached to the stand, the clutch 9, attached to the crank-shaft, the compressing-spring 8, the crank 3, the lock-lever 12, and the stops 20 and 21, substantially as herein specified.

In testimony whereof I have hereunto set my hand.

NATHANIEL O. GOLDSMITH.
